WILLIAM G. DAVIS, OF GRANITE CITY, ILLINOIS.

MEANS FOR CARBURATION.

1,227,530.

Specification of Letters Patent.

Patented May 22, 1917.

Application filed October 28, 1916. Serial No. 127,774.

To all whom it may concern:

Be it known that I, WILLIAM G. DAVIS, a citizen of the United States, residing at Granite City, in the county of Madison and 5 State of Illinois, have invented certain new and useful Improvements in Means for Carburation, of which the following is a specification.

This invention relates to certain new and 10 useful improvements in means for carburation, the peculiarities of which will be hereinafter described in the specification and particularly pointed out in the claims.

The object of my invention is to provide 15 a combustible gas from gasoline or like volatile liquid for automobile or like internal combustion engines, which gas will tend to effect a maximum explosive force in the combustion chamber with minimum amount 20 of fuel, and thereby develop the full rated horsepower of the engine and secure consequently an increased mileage per gallon of fuel for said automobile.

This gas is formed in the fuel supply tank 25 above the gasoline, or other volatile fuel contained therein, in gradually increasing volume as the fuel is used, and is ordinarily wasted when the fuel is supplied to the carburetor in the usual manner. My main object is to utilize this tank gas by superheating 30 it and combining it with any proportion of the regular charge from the carburetor, and to reduce such regular charge to a minimum; or even cut out the charge from the 35 carburetor altogether, and run the engine on this superheated gas alone, thereby minimizing the fuel consumption.

Referring to the accompanying drawing, the figure represents portions of an automobile engine, embodying my invention. For the purpose of illustration, I have shown a four cylinder engine, and designate the cylinders by the numerals 1, 2, 3, 4 respectively. 5 designates the intake manifold, 40 leading from the carburetor (not shown) and connected by the lobes 6 and 7 to the cylinders 1 and 2, 3 and 4 respectively. 8 designates the exhaust manifold for said cylinder, and 9 the pipe leading backward 45 therefrom to the rear of the machine. 10 designates a gasoline supply tank, preferably of the gravity type for illustrating my invention connected to the carburetor in the usual manner (not shown), and provided 50 with a tube 11 extending through the top of the said tank about two thirds of the way

to the bottom. The said tube is open to the air at the top, and normally extends below the surface of the gasoline in the tank, as indicated.

Other means for admitting air to the supply tank may be employed.

A pipe leads off from the top of said tank at 12, and then downward adjacent and preferably close to the pipe 9 as at 13 from 65 which it is led upward at 14 to a bend 15, preferably above the horizontal plane through the said tank. From the bend 15, the pipe leads downward having a regulating valve 16, just below said bend 15. At 70 or near the point 17 it enters the exhaust manifold passes forward and emerges at 18, and then bends and extends backward preferably above the exhaust manifold as shown at 19, and is provided with two branches 20 75 and 21, that enter the lobes 6 and 7 respectively of the intake manifold, and terminate in elbows or bends having their open ends so located as to discharge the respective jet of superheated gas directly opposite to the 80 current coming from the carburetor upward through the intake 5 on the way to the combustion chambers of the cylinders.

Thus when cylinders 1 and 2 draw the carburetor charge through 5 and divert it 85 into lobe 6 of the intake manifold, the elbow of the branch 20 presents its open end nozzle and the jet of superheated gas issuing from it, directly opposite and into the carburetor charge. On the other hand, when 90 cylinders 3 and 4 are drawing the charge into lobe 7, the elbow of the branch 21 opposes the charge with its nozzle and stream of issuing superheated gas. The resulting mixture being more perfect, secures higher 95 explosive effect and more perfect combustion, as I have demonstrated by actual use in my automobile engine.

The location of the pipe just described so 100 that it is in close proximity to or passes through exhaust manifold or other heating means causes the gas that is taken off by suction through said pipe from the top of the gasoline in the tank 10, to become heated to such a degree that it is practically superheated, and is delivered through the branches 20 and 21 directly against the charge drawn from the carburetor; and by such head on meeting of the superheated gas from the tank and the charge from the 110 carburetor, a more perfect mixture of explosive gas results, which when drawn into

the combustion chambers and ignited, burns with practically no deposit of carbon and with high explosive effect.

I have found by practical use of such arrangement as above described, that comparatively little charge from the carbureter is required, and that the gas taken from the top of the gasolene tank and superheated as described, is sufficient when delivered in regulated quantities, to operate an automobile efficiently at satisfactory speed, and with proportionately small consumption of gasolene.

I have shown the tube 11 as adapted to deliver the air below the surface of the gasolene and thereby impregnate it as it bubbles up to the surface, but other means for agitating the gasolene and impregnating the air so as to form a gas within said tank may be employed. Likewise, I have shown the preferred location of the pipe within the exhaust manifold for the purpose of superheating the gas within said pipe, though other means for superheating the said gas may be employed. I have located the branches 20 and 21 of said pipe so that their terminals pass into the lobes of the intake manifold between the cylinders 1 and 2, 3 and 4 respectively, as such location has given me good results in practice. I do not confine myself however to the exact location shown.

As before stated the speed of the machine is varied by regulating the quantity of superheated gas, passing through the pipes that I carried above and through the exhaust manifold. The regulating valve 16 is preferably operated by a link 22 connecting the lever of said valve to the crank 23 on a rod 24, mounted in bearings 26 on the steering rod 27 preferably, so that the operating arm 28 of said rod may be accessible to the operator at the steering wheel 29.

I have found by practical operation, that it is easy to regulate the amount of superheated gas, so that the resulting mixture does not contain much, if any, excess of carbon; and that the combustion of this comparatively dry superheated gas in the com-

bustion chamber of my machine not only gives a high explosive force with little consumption of gasolene, but little if any carbon is deposited within the cylinder.

When a higher speed is desired than the tank gas alone will develop, a regulated quantity of the carbureter charge is admitted to the intake manifold, is there broken up and intermixes with the stream of superheated tank gas, and then is drawn into the cylinders. The absorptive power of the comparatively dry and poor tank gas in its superheated condition, enables it to combine readily with and raise the explosive power of the richer, colder and damper carbureter charge. After a stop, the engine starts readily on the tank gas only, whether the engine is cold or hot.

I claim:

1. The combination with a gasolene engine, its supply tank and intake manifold, of a pipe leading from above the gasolene in said supply tank to and into the intake manifold,—the discharge end of said pipe being located so as to point directly into and opposite to the stream of carbureter charge entering said manifold,—and means to regulate the flow through said pipe.

2. The combination with a gasolene engine, its supply tank, intake manifold, exhaust manifold and exhaust pipe, of a pipe leading from above the gasolene in said supply tank along in close proximity to the exhaust pipe, then upward over or through the exhaust manifold, then branching and entering the respective lobes of the intake manifold, and then presenting the discharge ends of said branches directly opposite to the carbureter charge through said lobes, a valve for said pipe, and operative connections for regulating the proportion of tank gas to the carbureter charge, substantially as described.

In testimony whereof I have affixed my signature in presence of two witnesses.

WILLIAM G. DAVIS.
